UNITED STATES PATENT OFFICE.

HENRY KOHL, OF BOSTON, MASSACHUSETTS.

PROCESS OF PRODUCING MULTICOLOR PRINTS.

Application filed February 16, 1921. Serial No. 445,328.

To all whom it may concern:

Be it known that I, HENRY KOHL, a citizen of the United States, residing at Boston, in the county of Suffolk, and State of Massachusetts, have invented new and useful Improvements in Processes of Producing Multicolor Prints, of which the following is a specification.

This invention relates to processes of producing the various colorprinting plates necessary for the production of multicolored prints in general, and in particular, to the coloring of monochrome pictures, illustrations and reproductions, and processes for the production of the colorprinting plates, for their reproduction in the shape of multi-color prints, and has for its object to render such processes more expeditious, less expensive and less troublesome than heretofore.

20 The colorprinting plates required for the production of multi-colorprints have hitherto been obtained by the work of the lithographic artist and of the color-process photographer, using a finished colored picture 25 as a sketch or original for the basis of their work.

The invention consists in the improvements in the process of producing multi-color prints hereinafter described and 30 claimed.

Of the accompanying drawings forming a part of this specification,—

Figure 1 shows the face or printed side of a sheet constituting a monochrome print.

35 Figure 2 shows a transparent film having a color component, superimposed on the monochrome print of Figure 1.

Figure 3 shows the transparent film separated from the monochrome print, its face 40 side being outward.

Figure 4 shows the transparent film as it appears when placed face inward on a white background, and provided on its back with additional coloring.

45 Figure 5 shows a transparent film having a corrective or partial color component, for the correction of a multi-color print, or for the illumination of a monochrome, or for the production of a duograph.

50 Figure 6 is an edge view of the print and film assembled as shown by Figure 2.

I employ as a basis a monochrome, A, containing the various shades or tones of the subject in greys or browns, or whatever 55 tone the subject calls for, and in such manner as to give satisfactory rendition of its

shape and modulation. Such monochromes, ultimately to become multi-color prints, are frequently directly available as photographs, photoprocess and other prints and drawings, in many scientific, commercial and art subjects. I cover such monochrome A temporarily with a transparent film B, capable of receiving coloring on one or both of its surfaces, and produce on this film all shades and tints of coloring, that the subject in hand calls for, exactly as if coloring the monochrome on its own surface. When the coloring is completed upon this film, and whenever necessary, the usual register marks 60 on the monochrome have also been entered on the film, I remove the film B from the underlying monochrome A, and have now the color component of the picture completely 65 isolated from the monochrome part, as shown 70 by Fig. 3. Placing this color component against a suitable background, I obtain my color-printing plates in the usual manner by photographic color selection negatives. The final color-printing plates are made from 75 these in the usual way. Printing these color-printing plates in conjunction with prints from a printing plate made from the monochrome, produces the final finished multi-color prints.

When reproducing a painting or other colored subject, a photograph or photoprocess print of desired size and correct monochrome values is first obtained, and is then covered with a plain or uncolored transparent film and all tints and shades of color of the original are entered upon the film. The subsequent procedure is as above indicated. Regarding the application of coloring, it may be mentioned that often good 80 results are quickly obtained by applying coloring to both sides of the film. After finishing the coloring in its detail, as above described, on one side, the film B may be removed and laid reverse side up upon a white 85 surface. General tinting, sky, background tones, etc., can then be applied by air-brush or other means to the reverse side of the film. Figure 4 shows the film treated as last described, the reverse side and the coloring 90 last applied being outward. The original coloring on the obverse or front side furnishes sufficient outline and guidance for the removal of parts of such general coloring last applied at any portions, where it is not 95 wanted.

Where plates, representing the mono-

chrome part of a subject are at hand, a print of proper values may be made directly upon the reverse side of the film. The film is then placed upon a white background, 5 and the coloring executed upon the obverse side. When finished, the monochrome print on the reverse side is removed by a proper solvent. If desirable, additional coloring can now be applied to the reverse. The 10 transparent film having a monochrome print would present the same appearance, excepting as to its material, as monochrome print A, and the film, after the removal of the monochrome print, and the application of 15 additional color in place of the print, would appear as shown by Figure 4. A print made on paper, instead of on the film would appear reversed as to right and left, as compared with Figure 1. When making 20 negatives and printing plates from a color component obtained this way, proper care must be taken to obtain correct position as to right and left.

Where a multi-color print produced by 25 any process requires for satisfactory completion an additional color-printing or printings to emphasize or change its tones, I cover such multi-color print with a transparent film B² and apply thereto the color 30 tones and shades required, just as if making these corrections on the surface of the multi-color print itself. When completed, I remove the film, carrying now the color tones for the desired improved effect in the 35 shape of a corrective or partial color component which may appear as shown by Fig. 5, and produce from the same photo-process negative or negatives and photo-mechanical printing plate or plates, as the case may be, 40 and print the same in conjunction with the other printing plates of the multi-color print, or over the multi-color print.

Where a monochrome picture or print is to be made more effective by the addition of 45 another printing or printings, I proceed as in the case just described, producing on one or both sides of the superimposed film the desired effects. When separated, the transparent film carries a color component representing these effects, free from undesirable repetitions of the monochrome design and only on the parts wanted (see Fig. 5.) From such color component I obtain, as the case may be, the photo-process negative or 55 negatives and the photo-mechanical printing plate or plates to be printed in conjunction with a printing plate of the monochrome picture or print.

The monochrome picture A may be of 60 any description, or made by any process.

The film I employ at present, is celluloid of suitable weight and clearness, treated on both sides with a transparent coating of 65 gelatinous, albuminous, starchy or gummy substances, or a mixture of the same, capable

of receiving and holding the coloring. Other carriers and substances are also more or less suitable, but the above possesses greatest clearness and retention of size. It may be remarked, that in proving and in 70 the edition, it is desirable to print generally the monochrome part of the subject first, and this and the color-printing plates may be printed in any process, assuring register, but it is not necessary to employ the same 75 process for both. When possible, a final monochrome print, made on paper used for the edition, may be employed when making the color component. Where the color component has been made over a monochrome 80 of different size from the one finally desired, the color selection negatives are made to register to the size of the final monochrome print. Printing generally the monochrome part of the reproduction first, has the advantage, that register and strength of the color-printing plates can be easily seen and controlled, that the colors printed over the monochrome produce great transparency 85 and depth, and a wide range of shades of 90 color, and surprisingly true and artistic results, so that the fact of a monochrome being the basis of the picture is lost sight of.

It should be pointed out that my process furnishes the identical coloring of the artist, entirely separate from the monochrome part of the picture, and directly available for the photographic and photo-mechanical production of the color-printing plates; that no special outline or key-plate drawing, 95 impressions or offsets are required; that the photo-mechanically reproduced color-printing plates insure greater fidelity, wider range and better effect of coloring, than can be produced by the lithographic process in 100 the same number of printings, and that the work of drawing the colors is avoided.

Compared with three and four color photo-engraving, the difficulties of obtaining 110 satisfactory results are greatly reduced. In my process, the production of the monochrome foundation negative and print offer no more difficulty than the regular photographic copy or wash drawings, as color screens are not used. The color component, 115 being minus the monochrome part of the picture, shows no great contrast, and consequently, direct process color-selection negatives are easily made, resulting in the saving of two operations over the indirect process frequently employed. The color component carried on a transparent film, and the coloring executed in transparent colors, can be equally well photographed from either side, the use of a prism for obtaining correct position as to right and left is avoided, 120 and better color-selection negatives are more easily obtained.

In the printing of the edition of such 130 three or four color-processes, where the

monochrome, as well as the color values of the picture are obtained by the successive printing of the three or four color-printing plates, it is not only absolutely necessary 5 that these register perfectly, in order to produce clearness and sharpness of the detail of the picture, but the neutral tones must be perfectly balanced in the three or four color-printing plates, in order to appear as 10 neutral tones,—both requirements being difficult of accomplishment.

In my process, clearness and sharpness of the detail of the picture are obtained in one printing, i. e., the printing of the monochrome part and so are the neutral tones, and they only need to be brought to the correct color tone by tints of color contained upon the printing plates made from the color component of the picture. These color-printing 15 plates, representing the coloring of the picture more in the shape of broader washes, do not contain a constant repetition of the minutest detail of the picture, as is the case in the three or four color-processes referred 20 to, and consequently do not require such absolute register for their successful printing.

I claim:

1. That improvement in the process of 30 producing multi-color prints, which consists in associating a transparent film with a monochrome picture, coloring the film to produce a color component of the picture, and producing photo-mechanical printing 35 plates from the color component.

2. That improvement in the process of 40 producing multi-color prints, which consists in associating a transparent film with a monochrome picture, coloring the film to produce a color component of the picture, and producing photo-mechanical printing 45 plates from the monochrome picture and the color component.

3. That improvement in the process of 45 producing multi-color prints, which consists in associating a transparent film with a monochrome picture, coloring the film to produce a color component of the picture, making photographic color selection nega- 50 tives from the color component, and making photo-mechanical printing plates from said negatives.

4. That improvement in the process of 55 producing multi-color prints, which consists in associating a transparent film with a monochrome picture, coloring the film to produce a color component of the picture, making photographic color selection negatives from the color component, making photo-mechani- 60 cal printing plates from said negatives, and making a photo-mechanical printing plate from said monochrome picture.

5. That improvement in the process of

producing multi-color prints, which consists in super-imposing a transparent film 65 on a monochrome picture, coloring the film to impart to the picture, when the latter is viewed through the film, a color component of the picture, and producing photo-mechanical printing plates from the color component 70 after its removal from the picture.

6. That improvement in the process of producing multi-color prints, which consists in superimposing a transparent film on a monochrome picture, coloring the film to 75 impart to the picture, when the latter is viewed through the film, a color component of the picture, producing photo-mechanical printing plates from the color component after its removal from the picture, and producing from the monochrome picture another photo-mechanical printing plate.

7. The process of producing multi-color prints substantially as specified by claim 1, said process including the coloring of the 85 film on both sides to produce said color component.

8. That improvement in the process of producing multi-color prints, which consists in superimposing on a monochrome 90 print a transparent film, coloring the outer side of said film to produce a partial color component of said picture, removing the film from the monochrome, coloring the reverse side of the film to complete the color 95 component, photographing the color component from either side of the film, thus obtaining, without the employment of a prism, correct position as to right and left on color-printing plates, according to the requirements of the process employed for the printing of the monochrome and color parts of the picture.

9. That improvement in the process of color-printing which consists in superimposing 105 on a picture a transparent film, producing on said film a color component of the picture, designed to perfect the latter, making from said color component, after its removal from the picture, a photo-process negative, 110 and making a photo-mechanical printing plate from said negative.

10. That improvement in the process of producing multicolor prints, which consists in associating a transparent film with a monochrome picture, coloring said film on one or both sides, to produce the effect of a color added to the monochrome; separating the film from the monochrome, and making photo-process negatives and photo-mechanical printing plates from the color component designed to add a color-printing to the monochrome.

In testimony whereof I have affixed my signature.

HENRY KOHL.
